UNITED STATES PATENT OFFICE.

ANTHONY LASKY, OF BRIDGEPORT, CONNECTICUT.

LOCK.

1,375,521.

Specification of Letters Patent. Patented Apr. 19, 1921.

Application filed September 28, 1920. Serial No. 413,304.

To all whom it may concern:

Be it known that I, ANTHONY LASKY, a citizen of the United States, and a resident of Bridgeport, in the county of Fairfield and State of Connecticut, have invented a new and Improved Lock, of which the following is a full, clear, and exact description.

The invention relates to locks such as shown and described in the application for 10 Letters Patent of the United States, Serial No. 380,291, filed by me on May 10, 1920.

The object of the present invention is to provide a new and improved lock more especially designed for use on trunks and 15 similar articles and arranged to prevent picking of the lock and opening of the trunk by unauthorized persons.

Another object is to provide a lock of simple and durable construction and one 20 that is not liable to get easily out of order.

With these and other objects in view, the invention consists of certain novel features of construction as hereinafter shown and described and then specifically pointed out 25 in the claims.

A practical embodiment of the invention is represented in the accompanying drawings forming a part of this specification, in which similar characters of reference indicate corresponding parts in all the views. 30

Figure 1 is a sectional side elevation of the improved lock as applied and with the key shown in withdrawn position;

Fig. 2 is a cross section of the improved 35 lock on the line 2—2 of Fig. 1;

Fig. 3 is a plan view of the locking spindle; and

Fig. 4 is a reduced front elevation of the 40 lock as applied and with the parts in locked position.

The trunk on which the lock is shown applied comprises the usual body 10 and a cover 11, and on the said body 10 is secured the leaf 12 of a hinge 13 provided with 45 a leaf 14, to the rear face of which is secured the lock casing 15 by rivets or other suitable fastening devices 16. The casing 15 is adapted to pass into a cylindrical keeper 20 fed into an opening 21 formed in 50 the cover 11, as plainly shown in Fig. 1, and the said keeper is provided at its front with a flange 22 fastened by rivets or other fastening devices 23 to the cover 11.

Within the lock casing 15 are secured 55 front and rear casing members 25, 26, of which the front casing member 25 is pro-

vided with a hub 27 extending through an opening 28 formed in the leaf 14 of the hinge 13. In the casing members 25 and 26 is journaled a locking spindle 30 provided at its front end with a collar 31 flush at the outer face with the forward end of the hub 27, and this collar 31 is concentric with the hub 27 and is adapted to receive the tubular shank 35 of a key 36 having 60 a suitable handle 37 to permit the user to conveniently manipulate the key, as herein-after more fully explained.

The forward end of the shank 35 of the key 36 is provided with bits 38 and the 65 said shank 35 is provided on its peripheral face with a lug 39 adapted to pass through a slot 40 formed in the inner face of the head 27 to guide the shank 35 when inserted into the lock, that is, onto the collar 31 of the locking spindle 30. The rear end 42 of the locking spindle 30 is preferably made polygonal to carry a locking member 43, preferably of elliptical shape (see Fig. 4) and adapted to pass through a correspondingly shaped opening 44 formed in the back 45 of the keeper 20. It is understood that after the locking member 43 has passed through the opening 44 and about a quarter turn is given to the spindle 30 75 by the key 36, as herein-after more fully explained, then the locking member 43 engages the back 45 of the keeper 20 thus holding the locking member 43 in locking 80 position.

The spindle 30 is provided intermediate the collar 31 and the polygonal end 42 with an enlarged portion 50 provided in its peripheral face with longitudinally extending grooves 51 leading to openings 52 arranged on the forward end of the enlarged portion 50. The openings 52 are engaged by lengthwise extending tumbler pins 55 adapted to be engaged by the corresponding bits 38 of the key 36, and the said 95 tumbler pins 55 are normally held in forward position by spring 56 extending in the recesses 51 and abutting with their rear ends against the fixed casing member 26. The tumbler pins 55 are provided at their 100 rear ends with angular arms 57 normally engaging recesses 58 formed in the rear face of the casing member 25 thus holding the locking spindle 30 against turning. The rear face of the casing member 25 is spaced 105 from the front face of the casing member 26 to form an annular chamber 59 into

which are adapted to pass the angular arms 57 on pushing the tumbler pins 55 the corresponding distance rearwardly by the insertion of the proper key. It will be noticed 5 that when the arms 57 extend in the chamber 59 the spindle 30 is turned on turning the key 36 owing to the bits 38 engaging the forward ends of the tumbler pins 55. The angular arms 57 of the tumbler pin 55 10 are adapted to pass into recesses 61 formed in the forward face of the casing member 26 whenever the tumbler pins 55 are pushed too far rearward on the insertion of a wrong key. Thus the spindle 30 is normally held against being turned by the angular arms 57 engaging the notches 58 and the spindle is also prevented from being turned in case any one of the angular arms 57 engages a corresponding recess 61 15 in the casing member 26. The spindle 30 can only be turned when the angular arms 57 extend into the annular chamber 59. It is understood that the recesses 58 and 61 are in register with each other.

20 25 In practice, the tumbler pins 55 are alike in length, but the openings 52 through which the tumbler pins pass are of different length so that the forward ends of the several tumbler pins 55 are out of register, 30 that is, are in different transverse planes for engagement with the correspondingly stepped bits 38 of the tubular shank 35 of the key 36.

Having thus described my invention, I 35 claim as new and desire to secure by Letters Patent:—

1. In a lock, a lock casing, spaced members secured in the casing and provided at their spaced opposing faces with aligned recesses, 40 a spindle mounted to turn in the casing members, and having at its inner end a locking member, and a plurality of spring pressed and sliding tumblers mounted in the spindle, the said tumblers having angular 45 members adapted to engage either of the recesses of the members to prevent turning of the spindle and to enter the space between the said members to permit turning of said spindle.

50 55 60 65 2. In a lock, a fixed keeper having an elongated opening in its back plate, a lock casing, spaced members fixed in the said casing and provided at their spaced opposite faces with registering recesses, a spindle mounted to turn in the said casing members and having a locking member adapted to pass through the opening of the keeper to engage the back thereof on turning the spindle, and spring-pressed tumbler pins slidable 120 lengthwise on the said spindle and having angular arms normally engaging the recesses in one of the said casing members, adapted to pass into the space between the said member and into the recesses of the 125 other casing member.

3. In a lock, a lock casing provided with fixed front and rear members spaced apart and of which the front member is provided with a hub having a bit slot on the inner face, the opposing faces of said members 70 having aligned recesses, a locking spindle mounted to turn in the said casing members and having its front end extending into the said hub, spring-pressed tumbler pins slideable lengthwise on the said spindle and 75 adapted to be controlled by a key engaging the forward end of the spindle, the said tumbler pins having angular arms adapted to engage either of the recesses of the said casing members to hold the locking spindle 80 against turning or to pass into the space between the said casing members to allow of turning the locking spindle.

4. In a lock, a key having a tubular shank provided at the forward end with bits and 85 at the peripheral face with a lug, a keeper having an elongated opening, a casing extending into the keeper and provided with fixed front and rear members having their opposite faces spaced apart and provided 90 with registering recesses in their opposing faces, the said forward casing member having a hub adapted to receive the key shank, the hub having a slot for the passage of the said shank lug, a locking spindle mounted 95 to turn in the said casing members, and provided with a locking member adapted to pass through the opening of the keeper and engage the back thereof, and spring-pressed 100 tumbler pins slideable lengthwise on the said spindle and adapted to be engaged by the said key bits, the said tumbler pins having angular arms normally engaging the said recesses in the front casing member, the said arms being adapted to pass into the space 105 between the casing members to allow of turning the locking spindle on the insertion of the proper key and the said arms being adapted to pass into the recesses of the rear casing member to prevent turning of the 110 locking spindle on the insertion of a wrong key.

5. In a lock, a key having a tubular shank provided at the forward end with bits and 115 at the peripheral face with a lug, a casing provided with fixed front and rear members having their opposite faces spaced apart and provided with registering recesses in the opposing faces, the said forward casing member having a hub adapted to receive the key shank, the hub projecting through the casing and having a slot for the passage of the said shank lug; a locking spindle mounted 120 to turn in the said casing members, spring pressed tumbler pins slideable lengthwise on the said spindle and adapted to be engaged by the said key bits, the said tumbler pins having angular arms normally engaging the said recesses in the front casing member, the 125 said arms being adapted to pass into the 130 other casing member.

space between the casing members to allow of turning the locking spindle on the insertion of the proper key and the said arms being adapted to pass into the recesses of the 5 rear casing member to prevent turning of the locking spindle on the insertion of a wrong key, an elongated locking member on

the rear end of the said locking spindle, and a keeper in which the lock casing extends, said keeper having an elongated opening through which the said locking member of the locking spindle is adapted to extend and engage the back of the keeper. 10

ANTHONY LASKY.
